UNITED STATES PATENT OFFICE

2,460,955

INHALER

Paul H. Todd, Kalamazoo, Mich.

Application May 17, 1946, Serial No. 670,623

1 Claim. (Cl. 128—200)

1

The main objects of this invention are:

First, to provide an inhaler which when closed is effectively sealed to prevent evaporation of the medicament and to maintain the inhaler in a sanitary condition.

Second, to provide an inhaler embodying few parts and one in which the parts are economical to produce and assemble.

Objects relating to details and economies of the invention will appear from the description to follow. The invention is defined in the claim.

A preferred embodiment of the invention is illustrated in the accompanying drawing, in which:

Fig. 1 is a longitudinal section of an inhaler embodying my invention, the medicament carrying material being conventionally illustrated, the structure being considerably enlarged as compared to commercial sizes.

Fig. 2 is a cross section on a line corresponding to line 2—2 of Fig. 1.

Fig. 3 is a fragmentary side elevation with the cover removed.

The embodiment of my invention illustrated comprises a tubular medicament container 1 preferably formed of thin metal such as aluminum and having a convexly rounded nasal tip 2 with a central opening 3 therein. The base 4 is preferably molded of plastic material and is provided with a cylindrical portion 5 fitting within the lower portion of the container 1 and having an annular outwardly facing groove 6 therein into which the lower end 7 of the casing is pressed in closely fitting supporting relation. The groove is of curved section and the container wall being pressed therein provides a correspondingly outwardly facing groove receiving the resilient annular gasket 8.

This gasket is of relatively soft or yielding rubber or synthetic rubber and is contractingly engaged in the groove. It is preferably of circular cross section and projects substantially from the groove.

The container is provided with an air inlet opening 9 above the base member and is adapted to receive a medicament container such as cotton indicated at 10.

2

The casing or cover 11 is also tubular in shape and is provided with a closed convexly curved outer end and has its inner end rolled outwardly into a bead-like flange 12. The cover closes over the gasket in sealing retaining engagement therewith. The casing entirely encloses the container and is supported in concentric relation thereto.

Both the container and the cover may be formed of relatively light metal, the base member constituting a supporting and protecting element therefor.

The parts are simple and economical to produce and very easily and quickly assembled, the only machine operation in assembling being rolling or spinning of the lower end of the container into the groove.

I have illustrated and described a practical embodiment of the invention. I have not attempted to illustrate or describe other embodiments, as it is believed that this disclosure will enable those skilled in the art to embody or adapt the invention as may be desired.

Having thus described my invention, what I claim as new and desire to secure by Letters Patent is:

An inhaler comprising a base member having a cylindrical portion thereon and defining an annular groove therearound, a generally cylindrical container having one end pressed into said annular groove, an annular ring of elastic material positioned in said groove and a generally cylindrical cover member arranged to fit over said ring and be held in place thereby.

PAUL H. TODD.
